SAFETY FEATURE FOR CONTROL SYSTEMS

William J. McGoldrick, Minneapolis, Minn., assignor to Minneapolis-Honeywell Regulator Company, Minneapolis, Minn., a corporation of Delaware

Application January 28, 1939, Serial No. 253,309

6 Claims. (Cl. 158—28)

This invention is directed broadly to automatic control systems for fuel burners. It is concerned more particularly with the addition of a safety feature to the system disclosed in co-pending application Serial No. 253,337 filed January 28, 1939 in the name of John M. Wilson.

The main purpose of the invention is to provide a relatively simple control system for fuel burners in which no electromagnetic relays are used but which gives protection against failure of the fuel to ignite, flame failure after ignition has been obtained, and power failure. This protection is obtained by means of a combustion switch which closes when hot, and the present system is designed to prevent a start if the combustion switch should happen to stick in the hot position.

Other objects will readily become apparent as the following specification is read in the light of the accompanying drawing, the single figure of which diagrammatically illustrates a control system embodying my invention.

Indicated generally at 11 is a room thermostat comprising a bimetallic coil 12 and a switch arm 13 connected thereto at its free end and adapted to make contact with the stationary contact 14 on a decrease in temperature to a predetermined point. Although a room thermostat has been specifically disclosed, it will be apparent that this thermostat may be replaced by a boiler thermostat or pressure responsive device or any other type of control instrument desired.

Indicated generally at 15 is a safety switch comprising a pair of resilient contact blades 16 and 17 which are connected at one end to the brackets 18 and 19, respectively. These contact blades are biased downwardly for a purpose to be described later. The blade 17 carries an insulating block 18 which is adapted to cooperate with the upper end of the bimetallic timer 19 which is fixed at its lower end to the bracket 20. With the timer in the position indicated in the drawing, the upper end engages the block 18 and supports the blade 17 in such a manner that its contact 23 is held in engagement with the contact 24 carried by the contact blade 16.

Slidably supported in the plate 28 is a reset member 29 having two insulating members 30 and 31. Extending through the plate 28 is a stem 32 having a button 33 for the purpose of providing a means for manually raising the reset member of the purpose of resetting the safety switch.

Mounted on resilient blade 35 is a movable contact 36 which is adapted to cooperate with contact 37 carried by the free end of the bimetal timer 19. Closely associated with the timer 19 is an electric heating element 40 which on heating causes the timer to flex toward the left in a direction to cause engagement of the two contacts

36 and 37. Indicated generally at 41 is a combustion switch which comprises a switch arm 42 and a stationary contact 43. This combustion switch is provided with the usual slip friction mechanism so that the contacts will be closed when the thermal element of the switch (not shown) responds to an increase in temperature and open when the thermal element responds to a decrease in temperature. Due to the slip friction mechanism, the switch is responsive to a change in the direction of the temperature variation rather than to any predetermined temperature.

Pivoted at 50 by means of the arm 51 is a mercury switch 52 which comprises one pair of electrodes 53 and 54 and a second pair of electrodes 55 and 56 and a globule of mercury 57 which alternately closes the circuit between one pair of electrodes and the other pair of electrodes as the switch is tipped back and forth from one position to the other. The arm 51 is pivotally connected to a link 58 which in turn is pivotally connected to the bimetal timer 19 so that as the timer flexes in response to the action of the heater 40 it will tip the mercury switch 52.

The burner motor is diagrammatically illustrated at 60 and the ignition means at 61. It will be understood that the purpose of the burner motor is to deliver the fuel in the proper form to the combustion chamber where it is ignited by means of the ignition means 61. It will be noted that the burner motor and ignition means are connected in parallel so that the system is a constant ignition system.

Operation

35

In considering the operation of this system, assume that the room thermostat 11 is satisfied and has been satisfied for a sufficient length of time for the bimetal timer 19 to have returned to its cold position in which it is straight up and down as shown in the drawing. The normally closed safety switch will be in the position shown, the combustion switch will be in open position due to the fact that the last temperature change in the furnace was a decrease in temperature due to the extinguishment of the fire. The mercury switch 52 will be tipped to its counter-clockwise position at which time the circuit between the electrodes 53 and 54 will be open thereby de-energizing the burner motor and the ignition means and the globule of mercury 57 will bridge the electrodes 55 and 56.

Due to the fact that the burner motor is de-energized, the temperature in the room will begin to fall and eventually the bimetal element 12 will bring the switch arm 13 into engagement with its stationary contact 14. This action will establish the following circuit energizing the heater 40 for the bimetal timer 19: supply line 65, conductor 60

66, stationary contact 14, switch arm 13, bimetal element 12, conductor 67, bracket 18, resilient contact blade 16, contacts 24 and 23, contact blade 17, bracket 19, conductor 68, conductor 69, 5 heater 40, protective resistance 70, and conductor 71 which is connected to the other supply line 72. Energization of the heater 40 will cause the bimetal element 19 to flex toward the left which will tip the mercury switch 52 in a clockwise direction causing the mercury 57 to leave the electrodes 55 and 56 and bridge the electrodes 53 and 54. This will establish the following circuit to the burner motor and ignition means: supply line 65, conductor 66, room thermostat 11, conductor 15 15 67, safety switch 15, conductor 68, conductor 75, electrode 53, mercury 57, electrode 54, conductor 76, conductor 77, burner motor 60, and conductors 78 and 79 back to the other supply line 72. The conductors 80 and 81 connect the ignition 20 means 61 in parallel with the motor 60 from conductor 76 to conductor 79.

Energization of the burner motor and ignition means will normally produce combustion within the combustion chamber of the furnace which 25 will raise the temperature so that the thermal element of the combustion responsive switch 41 will move the switch arm 42 into engagement with the stationary contact 43. This will normally occur before the bimetal timer 19 has flexed far 30 enough to the left to bring the contacts 36 and 37 into engagement. After the timer has brought contacts 36 and 37 into engagement, the following shunt circuit is set up around the heater 40: from the upper end of heater 40, conductor 83, 35 switch arm 42, stationary contact 43, conductor 84, resilient contact blade 35, contacts 36 and 37, bimetal timer 19 and bracket 20 to which the lower end of heater 40 is connected.

Closure of this shunt circuit deenergizes the 40 heater 40 and the bimetal timer will immediately start to cool which will cause it to flex to the right breaking the shunt circuit at the contacts 36 and 37. As the shunt circuit is broken, the heater 40 will be reenergized which will again 45 cause the bimetal timer to heat and reengage the contacts 36 and 37. This action will continue as long as the room thermostat 11 maintains the circuit closed at 13-14 and as long as the combustion responsive switch 41 maintains the switch 50 42-43 in closed position. While the bimetal timer 19 is oscillating back and forth making and breaking contacts 36 and 37, the mercury switch 52 is also being oscillated, but at this time it is tipped far enough so that it maintains the circuit 55 closed between the electrodes 53 and 54 and hence maintains the burner motor 60 and the ignition means 61 energized. This is the normal running position of the system.

After a time the temperature in the room will 60 increase to the point where the bimetal element 12 will cause the switch arm 13 to disengage from the stationary contact 14 and this will break the circuit between the control system and the supply conductor 65 and the burner motor and ignition means will therefore be immediately shut down, the heater 40 will be deenergized and the bimetal timer 19 will return to its cold position as shown in the drawing.

The above description covers a normal cycle of 70 operation of this control system. Assume, now, that after the room thermostat has called for heat and the bimetal timer under the control of the heater 40 has closed the circuit to the burner motor and ignition means that for some reason or other combustion fails to take place. Under

these conditions, the combustion responsive switch will not close at 42-43 so that when the bimetal timer 19 has flexed to the left and closed the contacts 36 and 37 no shunt circuit will be set up around the heater 40. The timer 19 will 5 therefore continue to flex to the left pressing back the contact blade 35 until the free end of the timer 19 slips from beneath the insulating block 18 carried by the resilient contact blade 17. At this time the blade 17 will flex downwardly 10 due to its bias thus separating the contacts 23 and 24 and breaking the circuit to the burner motor and ignition means and also the heater 40. It will be noted that the insulating member 30 on the reset 29 prevents blade 16 from following 15 the blade 17 and maintaining the contacts 23 and 24 closed. The system is now shut down and the bimetal element is cooling but it is prevented from flexing toward the right due to the fact that the insulating block 18 on the blade 17 is in its 20 path of movement thereby locking it in its flexed position.

The system will remain in this condition until the reset member 29 is manually raised by pushing upwardly on the push button 33. This action will first raise the blade 16 out of the path of movement of the blade 17 and then raise the blade 17 until the insulating block 18 frees the bimetal timer 19 permitting it to return to its cold position. When the button 33 is released, 30 the blade 17 will be left in the position shown in the drawing and the blade 16 will return the contact 24 into engagement with the contact 23. The reset operation is arranged in this manner so that the switch contacts 23 and 24 cannot be 35 manually held in closed position. In other words, the switch is trip free. The system has now been returned to the position shown in the drawing and another attempt to start will be made if the room thermostat is still calling for heat. 40

Now assume that after the room thermostat has become satisfied and has shut down the system after a normal run, the contacts 42 and 43 remain stuck in closed position. It will be appreciated that under these conditions, the 45 system if allowed to start will not be protected against a failure to obtain combustion and raw fuel will continue to be pumped into the combustion chamber under these circumstances. In order to prevent the system from being started 50 under these conditions, the electrodes 55 and 56 have been provided in the mercury switch 52. When the bimetal timer 19 is in its cold position, the mercury 57 bridges the electrodes 55 and 56 and the following shunt circuit is set up around the heater 40 when the room thermostat calls for heat: from the upper end of heater 40, conductor 83, switch arm 42, contact 43, conductor 84, conductor 86, electrode 55, mercury 57, electrode 56, and conductor 87 back to the lower end of 60 heater 40. It will therefore be seen that if the contacts 42 and 43 are stuck in closed position showing the combustion responsive control to be inoperative that there will be a shunt circuit closed about the heater 40 and the heater will 65 therefore not be energized to cause the bimetal timer 19 to close the circuit to the burner motor and ignition means.

It will therefore be seen that I have provided a 70 control system for a fuel burner using no electromagnetic relays but which will protect against failure to obtain combustion and failure of combustion and also against the danger resulting from the combustion control switch becoming inoperative.

It will be appreciated that the above system has been shown merely for the purposes of illustration and that I intend to be limited only by the scope of the appended claims.

5. I claim as my invention:

1. In a fuel control system, in combination, an electrical fuel controller, a circuit therefor, a fuel controller switch in said circuit, electrical means which when energized closes said fuel controller switch and thereafter renders said fuel controller inoperative, a main switch for energizing said electrical means, circuit connections including a closed hot combustion responsive switch to prevent said fuel controller being rendered inoperative by said electrical means if combustion is established, and means to prevent closure of said fuel controller switch by closing said main switch as long as said combustion switch is closed, said means including a circuit shunting at least a portion of said electrical means, said circuit having therein said combustion switch and a switch that is closed when said fuel controller switch is open and open when said fuel controller switch is closed.
2. In a fuel supply control system comprising in combination, fuel supplying means, means for controlling said fuel supplying means comprising a timer, said timer having a first position in which said fuel supplying means is rendered inoperative, a second position in which said fuel supplying means is rendered inoperative, and an intermediate range between said two positions in which said fuel supplying means is rendered operative, electrical means, a condition responsive device for energizing said electrical means to move said timer slowly from said first position toward said second position, means for preventing said timer from moving into said second position comprising a combustion responsive switch having hot and cold positions, and a circuit controlled by said timer for preventing the energization of said electrical means by said condition responsive device when said timer is in the first position and said combustion responsive switch is in its hot position.
3. In a fuel supply control system comprising in combination, fuel supplying means, a timer, switch means in control of said fuel supplying means operated by said timer, said timer having a first position in which said switch means maintains said fuel supplying means deenergized, a normally closed safety switch also in control of said fuel supplying means, said timer having a second position in which it opens said safety switch to deenergize said fuel supplying means, said timer also having an intermediate range in which said switch means maintains said fuel supplying means energized, a condition responsive device for energizing said timer to start it moving from its first position toward its second position, means preventing said timer from assuming said second position comprising a closed-when-hot combustion responsive switch, and means controlled by said switch means for preventing said condition responsive device from energizing said timer when said timer is in its first position and said combustion responsive switch is in its hot position.
4. In a fuel supply control system comprising in combination, fuel supplying means, a circuit therefor, a circuit control means and a normally closed safety switch in said circuit, a thermal timer operatively connected to said circuit control means, a heater for said timer, a circuit for said heater, a condition responsive device in control of said heater circuit, said thermal timer having a cold position in which said circuit control means holds said fuel supplying means deenergized, an intermediate range in which said circuit control means holds said fuel supplying means energized, and a hot position in which said timer trips said safety switch to open position, a shunt circuit for said heater including a closed-when-hot combustion switch, a second switch completing said shunt circuit closed by said timer when it is in its intermediate range whereby said heater is alternately energized and deenergized as said timer alternately opens and closes said second switch, a second shunt circuit for said heater including said closed-when-hot combustion switch and a second circuit control means, said thermal timer being operatively connected to said second circuit control means to close it when said timer is in its cold position whereby said heater cannot be energized by said condition responsive device if said closed-when-hot combustion switch is in its closed position.
5. In a fuel supply control system comprising in combination, fuel supplying means, a circuit therefor, a mercury switch comprising a first pair of electrodes, a second pair of electrodes, and a globule of mercury for selectively bridging said electrodes, said first pair of electrodes being in said fuel supplying means circuit, a normally closed safety switch in said circuit, a thermal timer operatively connected to said mercury switch, a heater for said timer, a circuit for said heater, a condition responsive device in control of said heater circuit, said thermal timer having a cold position in which the mercury bridges said second pair of electrodes and not said first pair, an intermediate range in which said mercury bridges said first pair of electrodes and not said second pair, and a hot position in which said timer trips said safety switch to open position, a shunt circuit for said heater including a closed-when-hot combustion switch, a second switch completing said shunt circuit closed by said timer when it is in its intermediate range whereby said heater is alternately energized and deenergized as said timer alternately opens and closes said second switch, a second shunt circuit for said heater including said closed-when-hot combustion switch and said second pair of electrodes, whereby said condition responsive device cannot energize said heater when said timer is in its cold position and said combustion switch is in its hot position.
6. In a fuel control system in combination, an electrical fuel controller, a circuit therefor, a fuel controller switch in said circuit, electrical means which when energized closes said fuel controller switch and thereafter renders said fuel controller inoperative, a main switch for energizing said electrical means, circuit connections including a switch which is closed in response to the establishment of combustion for limiting the electrical energy delivered to said electrical means to an amount sufficient to maintain said fuel controller switch closed but not sufficient to render said fuel controller inoperative, and means to prevent closure of said fuel controller switch as long as said combustion switch is closed.

WILLIAM J. McGOLDRICK.
